United States Patent Office

Des. 231,150
Patented Apr. 2, 1974

231,150

RACQUET COVER

Lois B. Berry, 509 W. Grant Place, Chicago, Ill. 60614, and Susan Miller, 290 Drexel Lane, Glencoe, Ill.
60022

Filed Aug. 21, 1972, Ser. No. 282,080

Term of patent 14 years

Int. Cl. D3—01

U.S. Cl. D87—1 R

Fig. 1

Fig. 2

Fig. 3

Fig. 4

FIG. 1 is a perspective view of a racquet cover embodying our new design with a racquet handle being shown in broken lines for illustrative purposes only;

FIG. 2 is another perspective view showing the reverse side thereof;

FIG. 3 is a side elevational view thereof; and

FIG. 4 is an end elevational view thereof.

We claim:

The ornamental design for a racquet cover, as shown and described.
